UNITED STATES PATENT OFFICE.

FRANK O. ANDERSON, OF MINNEAPOLIS, MINNESOTA, ASSIGNOR TO ALFRED ANDERSON,
OF MINNEAPOLIS, MINNESOTA.

RING-EXPANDER.

1,139,149.

Specification of Letters Patent. Patented May 11, 1915.

Application filed March 30, 1912. Serial No. 687,300.

To all whom it may concern:

Be it known that I, FRANK O. ANDERSON, a citizen of the United States, residing at Minneapolis, in the county of Hennepin 5 and State of Minnesota, have invented certain new and useful Improvements in Ring-Expanders; and I do hereby declare the following to be a full, clear, and exact description of the invention, such as will enable others skilled in the art to which it appertains to make and use the same.

My invention relates to what is known as ring expanders, to-wit, devices for increasing the diameter of rings by a rolling 15 and drawing out process, and has for its object to generally improve the construction and operation of devices of this character.

To such ends, generally stated, the invention consists of the novel devices and combinations of devices hereinafter described and defined in the claims.

In the accompanying drawings which illustrate the invention, like characters indicate like parts throughout the several views.

Referring to the drawings, Figure 1 is a view in front elevation showing the improved ring expander with some parts broken away and some parts sectioned; Fig. 2 is a vertical section taken on the line $x^2 x^2$ on Fig. 1, some parts being shown in full; Fig. 3 is a horizontal section taken on the line $x^3 x^3$ on Fig. 1; Fig. 4 shows the 35 ring expander in side elevation, some parts being sectioned on the line $x^4 x^4$ on Fig. 1, and some parts being broken away; Fig. 5 is a view in elevation showing certain of the parts of the expander removed from 40 working position; and Fig. 6 is a view corresponding in line of its section to Fig. 3 but illustrating a slightly modified construction.

The frame 1 of the expander is a continuous rectangular metal structure, preferably in the form of a casting provided with a base 2. The said frame 1 is formed with a large rectangular opening, to the vertical edges of which, guide strips 3 are 50 detachably secured. Preferably, the said guide strips 3 are formed with flat backs and with centrally projecting ribs 4. Said strips 3 may be detachably secured to the vertical portions of the frame 1 in different 55 ways, but preferably, this is accomplished

by means of retaining screws 5 threaded through the sides of said frame and having reduced ends that are seated in depressions formed in the backs of said strips 3.

The numeral 6 indicates a bifurcated 60 platen or anvil block which, at its ends, is provided with grooves that receive the flanges 4 of the guide strips 3, so that the said platen will be held in working position seated at the bottom of the opening 1^a of 65 the frame 1. The laterally spaced bearing prongs or lugs of the platen 6 are formed with axially alined notches or open seats in which the ends of a short roller shaft 7 are detachably seated. A grooved platen 70 roller 8 is journaled on the central portion of the shaft 7 with its lower portion working between the bearing lugs of the platen 6. The peripheral groove 8^a of the said 75 platen roller 8 corresponds to the desired cross section of the ring which is to be expanded, and from this, it, of course, follows that for different rings, different platen rollers, having the properly formed grooves, will be employed. As the roller 80 shaft 7 may be picked from its seats in the platen 6 and easily withdrawn from the platen roller, the substitution of platen rollers is, of course, an easy matter.

Working in the frame opening 1^a above 85 the platen 6 is a presser head or block 9 having laterally spaced depending prongs, the vertical edges of which are formed with grooves that receive the ribs 4 of the guide strips 3, so that the said presser head is held 90 in working position and guided for vertical movements, by the said guide strips 3. Obviously, the guide strips 3 are, in themselves, held against displacement by the screws 5 and by the platen 6 and presser head 9. 95 When the screws 5 are slightly retracted or screwed outward, the said elements 3, 6 and 9 may together be moved laterally out of the frame opening 1^a. A so-called expanding shaft 10 is rotatively mounted and detachably seated in the depending prongs of the presser head 9 and works just above the platen roller 8. The said shaft 10 works through an elongated slot 11, in one of the vertically extended sides of the frame 1, and, 100 at its outer end, is provided with an operating crank 12. By endwise movement, the said shaft 10 may be inserted through the slot 11 and into its seats in the prongs of the presser head 9. The finger-ring Y is 105 110

applied on the shaft 10 by passing the said shaft endwise through the head while said ring is placed approximately in position over the platen roller 8 and between the 5 prongs of the presser head 9.

Working with threaded engagement through the top of the frame 1 is a strong pressure applying screw 13, the lower end of which is swiveled to the upper central portion 10 of the presser head 9. At its upper end, said screw 13 is provided with an end piece or wheel 14 by means of which, the desired power may be applied necessary to force the presser head 9 downward and thereby cause the shaft 10 to press the ring 15 Y into the groove of the platen roller 8. It will be noted that the pressure produced by the screw 13 on the head 9 is in a direct vertical line with the point where the shaft 20 10 presses the lower portion of the ring Y against the upper portion of the platen roller 8. This distributes the pressing force in such a way that the presser head 9 is not cramped within the frame 1 and the strain 25 on the frame 1 is divided equally between the laterally spaced vertical side portions thereof.

To guide the ring Y for rotary movements in a true vertical plane and to prevent wabbling movements of the said ring as it is rotated, I provide improved ring guiding devices, preferably comprising a pair of laterally spaced guide plates 15 located between the depending prongs of the presser head 9, 30 and at their upper ends pivotally attached at 16 to a web formed as a part of the said presser head. To the lower edge of each guide plate 15, two longitudinally spaced guide rollers 17 are journaled for independent 35 rotary movements. These rollers 17 are arranged to engage the opposite sides or edges of the ring Y and to hold the same for rotation in a true vertical plane. As the rear rollers 17 engage with a downwardly moving portion of the ring Y, and the front rollers 17 engage with an upwardly moving portion of said ring, it is evident that the said front and rear rollers will be simultaneously rotated in reverse directions, and 40 hence, the importance of their independent journals. These rollers, as is evident, firmly guide the ring as it is being rotated in the expanding action and afford practically no frictional resistance to the movement of the 45 ring and do not deface or distort the edges of the ring, inasmuch as they have a rolling contact therewith. The guide plates 15 are adapted to be vertically spaced at their lower or roller equipped edges, and to be independently adjusted by small but long screw rods 18 having threaded engagement with the depending prongs of the presser head 9 and with their inner edges engaging the backs of the said plates. At their outer ends, 50 the screws 18 are preferably provided with

knurled heads 19. One of the said screws projects outward through the upper portion of the frame slot 11 and is permitted vertical movements thereby, but the other screw rod 18 projects through a vertical slot 20 70 formed in the opposite side of the frame 1. Obviously, the shaft 10, the adjusting rods 18, and guide plates 15 all move vertically with the presser head 9.

By means of the adjusting screw 13, the 75 presser head and expanding shaft may be pressed downward so as to press the ring Y against the platen wheel 8 under any desired pressure; and when the said shaft is then rotated, the frictional engagement between 80 said shaft and the ring will cause the latter to rotate, and under the pressure thus applied, and the rotary movement of the ring, the said ring will be increased in diameter, or expanded. Its original cross section may 85 be widened, or a new cross section given thereto, by the use of a platen roller having a groove of the proper form. The extent to which the ring will be expanded will, of course, depend upon the pressure applied 90 thereto, and the number of rotations given the expanding shaft 10.

In a modified construction illustrated in Fig. 6, narrow guide strips or bars 3^a are substituted for the guide strips 3, and these 95 are seated partly in the grooves of the platen 6 and presser head 9 and partly in grooves 3^b formed in the vertical side portions of the frame 1. The set screws 5^a employed in this instance, need only to press against the 100 backs of the said strips 3^a. When the said parts 3 and 6 are to be removed, the guide strips 3^a must be let back entirely into the grooves 3^b.

The guide strips 3 (see particularly Fig. 105 5) are provided with longitudinal or vertical slots that correspond to the slots 11 and 20 of the sides of the frame 1, against which they are applied. This is, of course, necessary in order to permit the free vertical 110 movements of the presser head 9 and the shaft 10 and adjustable rods 18 which are carried thereby.

What I claim is:

1. In a ring expander, the combination 115 with a rigid endless supporting frame having an opening with parallel side walls, of detachable rigidly secured guide strips applied to the said parallel side walls of the opening of said frame, a presser head 120 having tongue and groove sliding engagement with said guide strips and normally held thereby interlocked to said frame but removable laterally from said frame with said guide strips, a platen roller journaled in the lower portion of the opening of said frame, and an expanding shaft detachably journaled in said presser head and working through a clearance passage in said frame. 125

2. In a ring expander, the combination 130

- with a rigid endless supporting frame having an opening with parallel side walls, of detachable rigidly secured guide strips applied to the said parallel side walls of the 5 opening of said frame, a presser head having tongue and groove sliding engagement with said guide strips and normally held thereby, interlocked to said frame but removable laterally from said frame with said guide strips, an anvil block in the lower portion of the opening of said frame interlocked to the lower portions of said guide strips, a platen roller journaled to said anvil block, the said presser head and anvil block being 10 normally held in coöperative alinement by said guide strips and presser head and being removable laterally from said frame with said guide strips.
3. In a ring expander, the combination 20 with a frame, of a platen roller supported by said frame, a presser head movable on said frame toward and from said presser roller, an expanding shaft journaled in said presser head, and ring guiding devices comprising laterally spaced pivoted guide plates, each having at its free edge a pair of guide rollers journaled for independent rotations and adapted to engage the sides of a ring to be expanded.
- 25 4. In a ring expander, the combination 30

with a frame, of a platen roller supported by said frame, a presser head movable on said frame toward and from said presser roller, an expanding shaft journaled in said presser head, and ring guiding devices comprising laterally spaced pivoted guide plates, each having at its free edge a pair of guide rollers journaled for independent rotations and adapted to engage the sides of a ring to be expanded, said expanding shaft project- 35 ing through a vertical clearance passage in one side of the said frame, and screw rods working through the sides of said presser head and engageable with said pivoted guide plates to adjust the same, the said screw rods 40 working through clearance passages in the sides of said frame.

5. In a ring expander, the combination with a frame, of a platen roller and coöperating expanding shaft mounted on said 50 frame, and coöperating pivoted ring guiding plates having independently movable rollers for direct engagement with the ring.

In testimony whereof I affix my signature in presence of two witnesses.

FRANK O. ANDERSON.
